SAFETY HANDLE FOR BATHTUBS

Edward M. Anderson and Samuel J. Shanabrough, Monaca, Pa.

Application January 17, 1934, Serial No. 707,019

1 Claim. (Cl. 4—185)

This invention relates to safety handles for bath tubs and has for the primary object the provision of grips for aiding a person in entering and leaving a tub so that the danger of a person slipping or falling will be reduced to a minimum and the grips are provided with mountings so that they may be readily applied to tubs of the conventional type.

With these and other objects in view this invention consists in certain novel features of construction, combination and arrangement of parts to be hereinafter more fully described and claimed.

For a complete understanding of our invention, reference is to be had to the following description and accompanying drawings, in which

Figure 1 is a top plan view illustrating a bath tub with a safety handle applied thereto and constructed in accordance with our invention.

Figure 2 is a transverse sectional view illustrating the same.

Figure 3 is an enlarged fragmentary sectional view showing the construction of the grip of the safety handle.

Figure 4 is a side elevation illustrating one of the mountings of the grip.

Figure 5 is a transverse sectional view illustrating a tub with a modified form of safety handle applied thereto.

Figure 6 is a fragmentary plan view illustrating the same.

Figure 7 is a side elevation illustrating one of the mountings of the modified form of our invention.

Figure 8 is a fragmentary plan view illustrating a tub with another modified form of our invention applied thereto.

Figure 9 is a sectional view taken on the line 9—9 of Figure 8.

Figure 10 is a fragmentary sectional view illustrating another modified form of our invention.

Referring in detail to the drawings, the numeral 1 indicates a conventional type of bathtub and of the character which fits closely to the floor and one wall of a bathroom. Mounted to the outer side wall of the tub 1 is a safety handle forming the subject matter of the present invention and consists of a pair of mountings 2 each having extending therefrom an apertured ear 3. Extending through the ears 3 of the mountings 2 is a shaft 4 on which is mounted a grip 5. The threaded ends of the shaft 4 project beyond the ears 3 and have threaded thereto knobs 6. The grip interposed between the ears and the knobs threaded to the ends of the shaft 4 maintain the device assembled.

Each mounting 2 is of substantially U-shape to fit over the edge of the tub 1, as shown in

Figure 2. A foot 7 is pivoted to one end of the mounting while the opposite end of said mounting has threaded thereto a stud 8 having swivelly connected thereto a foot 9. The feet 7 and 9 engage inner and outer walls of the tub 1 and by adjusting the stud 8 the mounting can be firmly secured in place on the tub. The feet 7 and 9 have secured to their gripping faces rubber or similar material.

To apply a grip to the inner side flange of the tub 1 or the flange located adjacent the wall, as shown in Figure 5, mountings 10 are provided, each consisting of a shank 11 to which the apertured ear 3 is formed. One end of the shank is curved, as shown at 12, to engage the tub, as shown in Figure 5, while the opposite end of the shank is formed with a rightangularly extending flange 13 to abut the wall of the room. Formed integrally with the last-named end of the shank 11 is a hook-shaped element 14 depending from the shank and adapted to fit in a notch formed in the wall of the room and under the flange of the tub. The shank 11 is recessed, as shown at 15, in which is positioned the foot 9, the stud 8 thereof being threaded to the shank. The foot 9 in this form of mounting cooperates with the hook-shaped element 14 in firmly securing the mounting to the tub.

In the type of bath tub as suggested in Figure 8 and which when in use is positioned away from the wall of the bath room, grips may be applied to opposite sides thereof by mountings 16 each of which consists of an arcuate-shaped body 17 carrying a suitable padding 18 to engage with the flange of the tub. An arm 19 is formed integrally with one end of the body 17 and has threaded thereto a stud 20 carrying a foot 21. The latter engages under the flange of the tub and thereby firmly anchors the body 17 in position to the tub.

Referring to our modified form of invention, as shown in Figure 10, each mounting to the grip consists of an arcuate-shaped body 22 to fit over the outer side edge of the type of tub shown in Figure 1 and integral with the body of the mounting 22 is an extension 23 that extends downwardly against the outer wall of the tub and has detachably connected thereto a bracket 24, the latter being secured to the floor of the bathroom.

Having described the invention, we claim:

A safety handle comprising a pair of mountings each of substantially U-shape, a foot pivoted to one end of each mounting, a second foot pivoted and adjustably connected to the other end of each mounting, and a grip connecting said mountings.

EDWARD M. ANDERSON.
